UNITED STATES PATENT OFFICE.

JOHN A. FOURNEY, OF OAKLAND, CALIFORNIA.

ELECTRIC EXTENSION PLUG.

Application filed November 9, 1922. Serial No. 599,820.

My invention relates broadly to plugs adapted to be fitted in the usual screw-threaded electric fixture socket so as to connect an electric-conductor thereto, and relates 5 more particularly to plugs of this character which are adapted to be connected to or disconnected from said type of socket by longitudinal movement rather than rotative.

An object of the invention is to provide 10 a plug of the particular character described which will permit quick action both in connecting and disconnecting the plug, and at the same time enable the plug to be firmly held in the socket and proper contact of the 15 conductors maintained even when the connected plug is subjected to considerable vibration and rough handling.

Another object is to provide an extremely 20 simple plug of the character described and one in which the various electric conductors are so arranged that no short circuiting thereof can be effected.

The invention possesses other objects and 25 features of advantage, some of which, with the foregoing, will be set forth in the following description of the preferred form of my invention which is illustrated in the drawings accompanying and forming part of the specification. It is to be understood 30 that I do not limit myself to the showing made by the said drawings and description, as I may adopt variations of the preferred form within the scope of my invention as set forth in the claims.

Referring to said drawings:

Figure 1 is a perspective view of the plug.

Figure 2 is a longitudinal sectional view thereof.

Figure 3 is a longitudinal section view 40 of the plug showing it engaged in the fixture socket, the section being taken through a different portion of the plug than that shown in Figure 2.

Figure 4 is a perspective view of the re- 45 leasable retaining lever of the plug.

Figure 5 is a transverse section of the plug taken on the line 5—5 of Figure 3.

Briefly expressed the plug in the preferred 50 embodiment of the invention comprises a block formed of an insulating material, a fixed contact at one side of the plug adapted to project into the socket threads and connected to one of a pair of electric conductors, a longitudinally-movable spring-pressed contact extending from one end of the block

connected to the other conductor of said pair and adapted to engage the central contact post of the socket, a lever fulcrumed on said block having a projection extending from the other side of the latter arranged 60 to resiliently engage in the socket threads, and manually operated means for retracting said projection so as to enable the block to be moved into or out of the socket.

A detailed description follows:

The plug as here illustrated comprises a block 6 made of a suitable insulating material and having a reduced cylindrical portion 7 which is adapted to fit in the usual screw-threaded opening 8 of the electric fixture socket 9. The unreduced portion 10 of the plug is recessed and houses the ends of the electric conductors 12 and 13. An insulating shell 14 encloses the portion 10 and is secured to the perforated flange 16 through which the conductors extend. Fixed in the portion 7 of the plug and projecting outwardly from one side thereof is an electrical contact 17 which is connected to the conductor 12 by suitable means 18 arranged within the block. 80 When the plug is engaged in the socket, the contact 17 fits between the threads 19 of the socket and thereby makes electrical connection with the electric lead associated with the metallic shell in which the threads 19 85 are formed.

Means are provided, which when the plug is inserted in the socket, resiliently engage the portion of the threads opposite the portion engaged by the contact 17. As here 90 shown said means comprises a lever 21 of the first class fitted and fulcrumed within a recess 22 formed in the side of the block opposite the contact 17. One arm of the lever is provided with an outward extension 23 which is disposed in substantially diametrical alignment with the contact 17. By means of a tension spring 24 operative against the other lever arm, the lever extension 23 is normally held extended from 95 the block. In this manner when the plug is engaged in the socket the extension 23 will engage between the threads 19 and thereby cooperate with the contact 17 to hold the plug firmly secured in the socket. 100 In order that the extension 23 may be retracted, such as when the plug is inserted in or removed from the socket, there is mounted in the block a slidable rod 26 which when moved inwardly, against the 105

last mentioned lever arm, rocks the lever and causes the extension to be withdrawn into the recess 22.

Means are provided for causing both the contact 17 and the projection 23 to be resiliently pressed against the lower face of the threads 19 when the plug has been properly fitted into the socket. As here shown said means comprises a rod 28 which is slidable longitudinally in the block and projects from the end 29 thereof. The rod is normally retained in extended position by means of a spring 30. In use the plug is inserted far enough into the socket to cause the outer end 32 of the rod to abut against the end face 33 of the socket with sufficient pressure to compress the spring 30. In this manner the members 17 and 23 will be forcibly pressed against the lower face of the threads and the plug will be rigidly held in the socket. In the present embodiment of the invention, the foregoing means is incidentally used as a means for establishing contact between the conductor 13 and the center-post contact of the socket. By referring to Figure 2, it will be noted that the inner end of the rod is connected to the conductor 13, whereas the outer end thereof is provided with a laterally extending head which is adapted to engage the center contact of the socket when the plug is inserted in the socket. Rotation of the rod is preferably prevented by means of the pin 36 which depends from the head and engages an opening 37 formed in the block.

As clearly shown in Figure 5 the members 17 and 23 present wide segments in transverse section, thus enabling them to engage a comparatively large surface of the threads 40 and thereby eliminating any tendency on the part of the plug to oscillate with respect to the socket when engaged therein.

The contacts 17 and 28 as well as the lever 21 are separated by comparatively thick sections or partitions 39 of the block thus insuring against any short-circuiting of said members.

I claim:

1. An attachment plug for screw-threaded electric-lamp-sockets, comprising an insulating block, a fixed contact member projecting from one side of said block connected to

an electric conductor and arranged to engage in the socket threads, a contact member projecting from one end of said block and mounted therein for relative longitudinal movement with respect thereto one end of said contact being connected to another electric conductor, a spring encircling said movable contact member and urging the other end thereof outward from the block, a lever having a projection at the other side of said block adapted for engagement with the socket threads, a spring normally pressing said lever so as to hold said projection extended from the block, and a manually operable plunger arranged to engage said lever so as to retract said projection. 55 60 65

2. An attachment plug for screw-threaded sockets comprising an insulating block, a fixed contact member projecting from one side of said block for engagement in the socket threads, a second contact member projecting from an end of said block, a lever of the first class fulcrumed in said block 75 and having an arm thereof providing a projection at the other side of said block adapted for engagement with the socket threads, a spring operative against the other arm of said lever so as to hold said projection extended from the block, and a manually operable plunger arranged to engage said second lever arm so as to rock the lever to retract said projection. 80

3. An attachment plug for screw-threaded sockets, comprising a block formed of an insulating material, a contact member projecting from one side of said block arranged to engage the threads of the socket, a lever of the first class fulcrumed on said block 90 and having an arm thereof provided with a projection normally disposed to engage socket threads oppositely of said contact member, a tension spring operative against the other arm of said lever to normally hold said projection in operative position, and a plunger manually operable against said second arm of the lever from said first side of the block to engage said lever so as to retract said projection. 95 100

In testimony whereof, I have hereunto set my hand at Oakland, this 21st day of Oct. 1922.

JOHN A. FOURNEY.
